UNITED STATES PATENT OFFICE.

WALTER S. ALLYN, OF THOMPSONVILLE, ILLINOIS, ASSIGNOR OF ONE-HALF TO
THOMAS G. PUCKETT, OF THOMPSONVILLE, ILLINOIS.

RESILIENT WHEEL.

1,105,600.

Specification of Letters Patent.

Patented Aug. 4, 1914.

Application filed June 30, 1913. Serial No. 776,683.

To all whom it may concern:

Be it known that I, WALTER S. ALLYN, a citizen of the United States, residing at Thompsonville, in the county of Franklin 5 and State of Illinois, have invented certain new and useful Improvements in Resilient Wheels, of which the following is a specification, reference being had to the accompanying drawings.

- 10 This invention relates to new and useful improvements in resilient wheels and more particularly to a resilient hub for vehicle wheels, the object of the invention being to provide a resilient hub which will permit 15 movement of a wheel in various directions and absorb the shock and jar caused by driving over rough and uneven roads so that the same will not be conveyed to the body of the vehicle.
- 20 Another object of the invention is to provide a resilient hub which will possess advantages in points of efficiency and durability, is inexpensive of manufacture and at the same time is simple in construction and 25 operation.

With the above and other objects in view, this invention consists in the novel features of construction and the combination and arrangement of parts to be hereinafter more 30 fully described, pointed out in the claims and shown in the accompanying drawings, in which—

Figure 1 is a front elevation, parts being broken away and in section; Fig. 2 is a 35 transverse sectional view; Fig. 3 is a plan view of the disk; Fig. 4 is an elevation of the plate formed upon the outer end of the driven axle; Fig. 5 is an elevation of the plate upon the outer end of the driven axle 40 illustrating the side opposite that shown in Fig. 4; and Fig. 6 is a bottom plan view of the slide member.

Referring more particularly to the drawings, 1 indicates the axle of a vehicle and in 45 the present instance the rear axle is to be described and illustrated in connection with my invention. Mounted upon the axle 1 and adapted to inclose the same is a casing 2 upon the outer end of which is formed a frame 3. This frame is preferably rectangular in cross section, as illustrated in Fig. 1, and is provided with an extension 4 in 50 which are arranged the coil springs 5. Formed integral with the outer end of the

axle is a circular plate 6, which is provided 55 upon its rear face with a brake drum 7 and further provided at its central portion with an annular shoulder 8 which is adapted to abut against the end of the casing 1 to prevent longitudinal movement of the axle. 60 The plate 6 is provided upon one face thereof with outwardly projecting pins or lugs 9 which are adapted to be arranged within the slots 10 formed within the disk 11 whereby the disk will be rotated upon the rotation 65 of the axle. Formed upon the inner end of the stub axle 12 is an annular plate 13 upon the inner face of which are formed the inwardly projecting pins or lugs 14 which are preferably arranged at right angles with 70 respect to the pins 9 and adapted to be disposed within the slots 10' of the disk 11 whereby upon the rotation of the axle and the disk, the stub axle 12 will be rotated therewith. The plate 13 is rotatably 75 mounted within the opening 15 formed in the slide member 16 and arranged between the walls of the slide 16 are the grooves 18 which are adapted to receive the inwardly extending edges 19 of the frame 3 so that 80 the slide member 16 will be guided throughout its movement. The coil springs 5 are arranged within the extension 4 and are adapted to be disposed between the closed end thereof and one side of the slide 16 so 85 that the slide is resiliently retained within the frame 3. Mounted upon the stub axle 12 for rotation thereon is a hub 20 which is provided with the usual radially projecting 90 spokes 21.

From the above description it will be readily apparent that upon the rotation of the axle 1 the plate 6 will rotate and the pins 9 engaging within the slots 10 of the disk 11 will rotate the disk and the stub axle 12, 95 upon which the hub 20 is mounted, will be rotated through the medium of the pins 14 formed upon the plate 13 and projecting within the slots 10' of the disk 11. It will be readily apparent that by having the pins 100 9 and 14 arranged within the slots 10 and 10' that various movements of the wheel will be permitted, the coil springs 5 absorbing any shock or jar which will eliminate the same from being conveyed to the body 105 of the vehicle. It will also be apparent that the device can be quickly taken apart for repairs or readily set up for use and it will

be also seen that the device itself is extremely simple in construction and can be manufactured at a comparatively low cost.

While I have shown and described the preferred form of my invention, it will be obvious that various changes in the details of construction and in the proportions may be resorted to for successfully carrying my invention into practice without sacrificing any of the novel features or departing from the scope of the appended claims.

What I claim is:—

1. A device of the class described including a driven axle, a casing therefor, a frame carried by the casing, a plate upon the end of the axle and rotatable within the frame, a slide member movable in said frame, a stub axle having a plate rotatable within the slide member, a disk disposed between said plates and means carried by the plates and engaging the disk to impart motion to the stub axle.

2. A driven axle, a plate carried thereby, a stub axle having a plate formed upon one end, a disk arranged between said plates and means carried by said plates and adapted to engage with the disk to impart motion to the stub axle.

3. A device of the class described including a driven axle, a plate carried thereby, a stub axle having a plate formed upon one end, a disk arranged between said plates and provided with slots, pins carried by said plates and adapted to engage within said slots whereby to impart motion to the stub axle.

4. A device of the class described including a driven axle, a casing thereon, a frame

carried by the casing, a plate carried by the axle and rotatable within said frame, a slide member mounted in the frame, and provided with a central opening, a stub axle having a plate rotatable within said opening, coil springs disposed between the slide member and one end of the frame, a disk arranged between said plates and provided with slots, and pins carried by said plates and adapted to be arranged within said slots to impart motion to the stub axle.

5. A driven axle, a casing thereon a frame supported by said casing, a plate rotatably supported in said frame, and having wheel supporting means and said axle and plate having co-acting means to cause the same to rotate in unison.

6. A driven axle, a casing thereon a frame supported by said casing, a plate relatively movable within said frame and adapted for rotation, said plate having wheel supporting means and said axle and plate having co-acting means to cause the same to rotate in unison.

7. A driven axle, a casing thereon a frame supported by said casing, a movable plate supported within said frame, wheel supporting means carried by said plate, a disk arranged between the axle and the plate, and means carried by the axle and plate adapted to engage with the disk to impart motion to the wheel supported means.

In testimony whereof I hereunto affix my signature in the presence of two witnesses.

WALTER S. ALLYN.
